(57) **CLAIM**

The ornamental design for a tab for helmet shield, as shown and described.

DESCRIPTION

FIG. 1 is a front elevational view of a tab for helmet shield showing my new design with the tab attached to the helmet shield shown in broken lines;

FIG. 2 is a back view thereof;

FIG. 3 is a left side view thereof;

FIG. 4 is a right side view thereof;

FIG. 5 is a top plan view thereof;

FIG. 6 is a bottom plan view thereof;

FIG. 7 is a partially enlarged view of a cross sectional view taken in the 7—7 line of FIG. 5;

FIG. 8 is a partially enlarged view of a cross sectional view taken in the 8—8 line of FIG. 5; and,

FIG. 9 is a top front perspective view of FIG. 1.

The portions shown by broken lines are for illustrative purposes only and form no part of the claimed design.
